UNITED STATES PATENT OFFICE.

PERCY SIMPSON, OF LONDON, ENGLAND.

PRINTER'S QUOIN.

1,254,370.

Specification of Letters Patent. Patented Jan. 22, 1918.

Application filed July 27, 1917. Serial No. 183,102.

To all whom it may concern:

Be it known that I, PERCY SIMPSON, a subject of the King of Great Britain, and residing at 18-19 Bowling Green Lane, Farringdon Road, London, England, have invented certain new and useful Improvements Relating to Printers' Quoins, of which the following is a specification.

This invention relates to quoins such as 10 are used by printers in locking up type in the chase. Such quoins may however be used for a variety of other purposes in connection with printing work.

It is the object of the present invention to 15 provide an improved form of screw quoins, the parts of which cannot possibly fall apart, while the construction is somewhat simplified and improved in other respects, and the possible range of expansion is made greater 20 for a given size of quoins.

The invention is illustrated in the accompanying drawings which show by way of example some forms of construction in accordance therewith.

25 Figure 1 shows a top plan view of a single quoins, and

Fig. 2 shows a vertical section thereof on the line A—B of Fig. 1;

30 Fig. 3 shows an underneath plan view of the quoins;

Fig. 4 shows a top plan view thereof with the quoins fully expanded, but with the screw removed;

35 Fig. 5 shows a vertical section of the quoins as expanded, taken on the line C—D of Fig. 4, and showing the screw in position;

Fig. 6 shows in elevation the inner face of one of the blocks of the quoins before it is made up;

40 Fig. 7 shows in perspective view the wedge piece before it is inserted in the quoins;

Fig. 8 shows in perspective view a smaller type of quoins partially expanded;

Fig. 9 is a perspective view showing a double quoins with the blocks closed together.

Referring first to Figs. 1 to 7, *a* and *b* are the two blocks of the quoins and *c* is the wedge piece. The screw *d* engages in a threaded hole at *e* in the wedge piece *c*, and 50 its head bears upon shoulders at *f* on the blocks *a* and *b*, so that as the screw is turned, the wedge *c* is drawn up, pressing the blocks *a* and *b* apart owing to the engagement of the inclined faces of the wedge against the 55 inclined faces at *g* on the blocks. The wedge *c* has projecting tongues *h* at its ends which

engage in slots formed at *k* in the blocks so that as the wedge falls or is forced down between the blocks it draws them together, and prevents them from coming apart. The 60 studs *l* are secured by being forced into the blocks, one stud *l* being forced into each block while a hole *m* in a corresponding position receives the end of the stud from the opposite block. The projecting ends of the 65 studs are somewhat tapered as indicated.

In assembling the device, the wedge is first 70 engaged by means of its tongues *h* with the grooves *k* of the blocks and then the studs *l* are driven in. As soon as these studs are 75 driven in it becomes impossible afterward to separate the parts of the quoins without driving out the studs again. This is the case because the wedge *c* can only slide out upwardly while the blocks separate, and the 80 studs *l* prevent the wedge from rising beyond the height which it attains when its upper face comes against the studs *l* as in Fig. 5.

The quoins shown in Fig. 8 has the same 85 essential parts as that shown in Figs. 1 to 7, but the screw *d* instead of having a rectangular aperture for engagement by a four-sided key, has a slot for engagement by a screwdriver. The quoins shown in Fig. 8 is of 90 smaller pattern having a smaller range of movement.

The quoins shown in Fig. 9 is the same as that shown in Figs. 1 to 7 except that the blocks *a* and *b* are longer and the wedge, 95 screw and studs are duplicated.

It will be seen that in each construction illustrated, the studs *l*, *m* which guide the blocks as they move together are so placed that they limit the upward movement of the 95 wedge *c*, thereby limiting the expansion of the quoins without the necessity of employing any headed studs or the like for the purpose. The wedge piece *c* cannot come out of the quoins unless the studs *l*, *m* above referred to are removed, and these studs may be driven into place, or screwed, the one in one block of the quoins and the other in the other block of the quoins as already stated. Hence, when a quoins is made up as above 100 described, no matter how it is handled it is impossible for the two blocks *a*, *b*, to come apart and for the wedge *c* to fall out, and the parts are thus also preserved from liability to damage which might be caused by 105 their being frequently taken apart and put together or interchanged. By making the 110

studs *l*, *m*, somewhat tapering at their ends, and the tongues *h* and grooves *k* so that they are not a very tight fit, it is made possible for the quoin blocks *a*, *b*, to take up a 5 slightly inclined position, so that as the quoin expands it can adapt itself to lock truly against the faces with which it is intended to engage if these faces are not quite parallel. As the stud *l* or *m* projecting from 10 each block engages in a hole in the opposite block, it is possible for the quoin to be expanded by the full width of a block, *i. e.* the full projecting length of each stud, that length being equal to the width of the block. 15 A slight further expansion even may be allowed, while the ends of the studs come out a little way from their holes, as the tongues *h* on the wedge piece act to some extent as guides which will bring the blocks 20 together again with the studs *l*, *m* engaging in their holes.

Having thus described my invention what I claim as new and desire to secure by Letters Patent is:—

25 1. A screw quoin comprising a pair of blocks with inclined faces and undercut grooves formed therein, a wedge piece with projecting tongues adapted to engage in

the undercut grooves and to slide therein, a screw having a head bearing on the blocks, 30 the shank of said screw engaging in a threaded recess in the wedge piece, and means for guiding the blocks in their expanding and contracting movements away from and toward one another, said guiding 35 means being adapted also to limit directly the upward movement of the wedge piece and consequently the expanding movement of the blocks.

2. A screw quoin comprising a pair of 40 blocks with inclined faces and undercut grooves formed therein, a wedge piece with projecting tongues adapted to engage in the undercut grooves and to slide therein, a screw having a head bearing on the blocks, 45 the shank of said screw engaging in a threaded recess in the wedge piece, and two studs one secured in one block and the other secured in the other block, said studs projecting and engaging freely in holes in the 50 opposite blocks, and being so disposed as to form stops directly limiting the upward movement of the wedge piece relatively to the blocks.

PERCY SIMPSON.
